RING GRINDING FIXTURE

John H. Thompson, Grand Rapids, Mich., assignor to General Motors Corporation, Detroit, Mich., a corporation of Delaware

Filed Feb. 7, 1961, Ser. No. 87,641
5 Claims. (Cl. 51—215)

This invention relates generally to industrial fixtures and more particularly involves apparatus and a method to individually feed and position large numbers of piston rings for grinding.

One of the important objectives of the invention is to provide apparatus which is adapted to grind the peripheries of a large number of split piston rings one at a time.

A further objective of the invention is to provide a unique method for achieving such individual grinding.

The advantages of such a fixture and method are several. First, a more uniform quality ring is obtained which has zero point protrusion at ring gap. Second, any desired true cylindrical shape can be produced on the ring diameter. Finally, each piece may be produced at a lower net manufacturing cost and peripheral lines on the ring diameter may be obtained to provide more uniform seating.

The special fixture which forms the subject of this invention is adapted to be mounted on and used in conjunction with a chucking-type grinder.

For a more detailed understanding of the invention and the objects and advantages thereof, reference may be made to the drawings in which:

FIGURE 1 is a side view in elevation of the special fixture.

FIGURE 2 is a view in plan taken substantially on the line 2—2 of FIGURE 1 showing certain parts broken away and in section to more clearly illustrate details of the device.

FIGURE 3 is a view similar to that of FIGURE 2 except that it has been substantially enlarged and other portions broken away to show one of the rings being received in the tapered area in front of the special carrier for locating the ring for grinding.

FIGURE 4 is similar to FIGURE 3 except that it shows the ring being carried forward in the tapered area by the carrier up against the grinder face plate where it is further compressed in the tapered area so as to close the gap in the ring.

FIGURE 5 again is like FIGURES 3 and 4 except that the live center or tailstock is shown clamping the ring against the grinder face plate with the carrier retracted so that the ring is in final position for grinding.

FIGURE 6 shows certain details of the magazine or loading bar on which the rings are placed prior to being fed one at a time for grinding.

FIGURE 7 illustrates further details of the magazine including how the rings are retained thereon and biased into the loader attachment.

FIGURE 8 is a view taken substantially on the line 8—8 of FIGURE 7 with parts broken away and in section illustrating how the magazine is mounted and also the operation of the keys or tabs which retain the rings on the magazine.

FIGURE 9 is a view in elevation taken substantially on the line 9—9 of FIGURE 6 illustrating the loader attachment and how the rings are initially compressed and fed into a tapered portion of the fixture adapted to close the ring gap.

Referring now to the drawings and particularly FIGURE 1, the special fixture is shown to include a base plate member indicated by a numeral 2. Mounted on the base 2 by brackets 4 is the magazine or loading bar assembly indicated generally by the numeral 6.

2

Referring particularly to FIGURES 2, 6, 7, 8 and 9, it will be observed that this magazine includes an elongated cylindrical member 8 having upper and lower diametrically opposed slots 10 and 12, respectively. The cylindrical member 8 is provided with a guide bar 14 (see FIGURES 2 and 8) which is secured thereto by welding and which in turn is fixed to the brackets 4 by the studs 16. The guide bar 14 is dimensioned so that the rings 18 mounted on magazine 6 will slide therealong and the gaps thereof will just receive the bar.

10 To assure that the rings 18 will move into the loader attachment, which is indicated generally by a numeral 20, a pair of keys 22 have been provided which engage the last or outermost ring. These keys are movable radially in a plate assembly 24 (see FIGURE 8) so that they enter slots 10 and 12. Their radial movement is controlled by a rod and handle assembly 26 extending axially through the cylindrical member 8 to the plate assembly 24 which has on an end thereof a pair of cam pieces 28 to engage the innermost ends of the keys 22. The keys 22 may be moved radially outwardly by rotation of the rod 26 and operating handle 30 on the opposite end thereof. It will be noted particularly in FIGURE 7 that the keys or fingers 22 are normally biased radially toward the center of plate assembly 24 by a small helical spring 32 connected between pins 34 fixed to each key 22 and riding in slots 36 in the plate assembly 24. It will be appreciated that it is necessary to be able to retract the keys 22 in order to load the rings 18 on the magazine.

20 When the keys 22 are in their outermost radial position so that they engage the last or outermost ring on the magazine, the rings are all biased toward the loader attachment indicated generally by the numeral 20. This bias is achieved by means of a helical coil spring 38 which is fastened between the plate assembly 24 and an anchoring plate 40 fixed in the end of the cylindrical member 8 at its end adjacent the loader attachment 20. To further assure that the rings 18 are received in the loader attachment 20, a pair of permanent magnets 42 have been mounted in the outermost plate 44 of loader attachment 20.

30 Referring now particularly to FIGURE 9, it will be observed that the loader attachment indicated generally by the numeral 20 is made up of a plurality of flat plates which provide a flat tapered clearance 46 therebetween for the reception of a single ring. Also located in this flat clearance is a formed plate pusher 48 which is energized or actuated in a lineal direction by suitable hydraulic or pneumatic means not shown. With a ring received in the flat clearance 46, energization of the plate pusher 48 will move the ring in the area 46 in the direction of the taper thereof thereby compressing the ring and tending to close its gap. As the piston ring is forced ahead by the plate pusher 48 it enters through a slot 50 in the cylindrical carrier of the fixture indicated generally by a numeral 52. The carrier 52 as best seen in FIGURES 2, 3, 4 and 5 is mounted for reciprocal movement in a bore 54 which is formed in cylindrical supporting assembly 56 mounted on plate 2.

40 Movement of carrier 52 backward and forward is accomplished by energization of a hydraulic servo 58 and a suitable driving linkage 60. Carrier 52 is provided with a bore 62 which, it will be noted, has a small axially extending taper 64 immediately behind the slot 50 therein. Immediately forward of the slot 50 is a ring 66 fixed to the end of the carrier which forms an abutting shoulder 68 to prevent the ring 18 from falling out of the forward end of the carrier.

50 Assuming now that the carrier is moved forward by energization of the servo 58, the ring 66 will enter an annular opening or recess 70 adapted to receive it. The opening 70 is provided in a radial flange 72 provided on

the face plate 74 of the grinding fixture. As the ring 66 enters slot 70 because of the forward movement of carrier 52, the ring 18 will be further compressed by reason of its engagement with face plate 74 and the small taper 64. Thus the ring 18 will be securely clamped against the face plate 74 with its gap closed.

It will be noted that the carrier 52 has located in the center thereof of a live center or tailstock indicated generally by a numeral 76. This tailstock 76 may be independently energized by servo 77 so that it also can move forward. As it does so, its face plate 78 engages the ring and also clamps it securely against the face plate 74 of the grinding fixture. Once the ring is securely clamped between the plates 74 and 78, the carrier 52 may now be retracted (see FIGURE 5) leaving the piston ring outer face open for grinding by the abrading tool of the grinder shown in phantom and indicated by a numeral 80.

It will be observed that the live center or tailstock 76 includes tapered roller bearing assemblies 82 adapted to take both thrust and radial loads in order to allow the ring 18 clamped between plates 74 and 78 to rotate with these plates as the face plate 74 of the grinding fixture is rotatably driven by a suitable power means such as an electrical motor. When the grinding operation has been completed the tailstock is moved away from ring 18 to the position shown in FIGURE 3 by energization of servo 77. The ring 18 will then drop away from face plate 74 and the fixture is ready to receive the next ring 18 for grinding.

From the foregoing it may now be appreciated that a unique grinding fixture has been provided and a method offered whereby piston rings may be fed one at a time, compressed and clamped in proper position to enable them to be individually ground.

I claim:

1. A ring grinding fixture comprising means for radially compressing the ring including means forming a flat elongated substantially rectangular clearance tapered at one end along the plane of said clearance and having an aperture therein for the reception of a split piston ring in the plane of said clearance, a ring pusher movable back and forth in the plane of said clearance adapted to engage one side of a split ring therein and push it in the direction of said taper, means for clamping the ring when compressed, means for turning said clamping means with the ring clamped thereby and means to release said clamping means.

2. A ring grinding fixture comprising first means for radially compressing the ring including means forming a flat elongated substantially rectangular clearance tapered at one end along the plane of said clearance and having

an aperture therein for the reception of a split piston ring in the plane of said clearance, a ring pusher movable back and forth in the plane of said clearance adapted to engage one side of a split ring therein and push it in the direction of said taper, a rotatable face plate, second means to move said compressed ring against said face plate, third means to hold said ring against said face plate for rotation therewith, means to withdraw said second means, and means to release said third means.

10 3. For use in combination with a ring grinding fixture, means to individually radially compress the rings to be ground comprising means forming a flat elongated substantially rectangular clearance tapered at one end along the plane thereof and having an aperture therein for the reception of a split piston ring in the plane of said clearance, a ring pusher movable back and forth in the plane of said clearance adapted to engage one side of a split ring therein and push it in the direction of said taper.

20 4. The combination claimed in claim 3 which further includes a magnet mounted on said means forming said clearance to attract a ring through said aperture.

25 5. The combination claimed in claim 3 which further includes a ring magazine extending transversely from the means forming said clearance in line with said aperture and means on said magazine tending to force any rings thereon toward said aperture.
